THREAD TRAP FOR SHUTTLES

Wilfrid Joseph Gosselin, Methuen, Mass., assignor to U S Bobbin & Shuttle Co., Providence, R. I., a corporation of Rhode Island

Application July 3, 1946, Serial No. 681,265

6 Claims. (Cl. 139—223)

1

This invention relates to shuttles of the automatic or self-threading type but it can be used equally well on hand-threading shuttles of many types.

The main purpose is to provide a shuttle having a body of wood or other suitable material with a metal shuttle block, both so arranged that the thread running off from the bobbin during or after transfer can go down through a longitudinal threading chamber underneath a nose and then down and back diagonally through a threading slot toward the outside of the shuttle and thence up and into a shuttle eye hole where it is trapped in position in such a way that it cannot unthread, if at all, except under the most unusual and unlikely conditions.

The principal new features are the arrangement of the front of what I will call the shuttle block eye projection and the back edge of the shuttle block recess whereby the back edge of the wood at the front of the shuttle block recess slightly overlaps the front edge of the eye projection of the block, and the formation of the shuttle eye projection with a transverse eye hole at the inside end of which is a bearing pin and at the front and back of the outside or outlet of which there are preferably upwardly extending guide and friction pins which are driven up into or positioned in pin holes extending up from the bottom of the shuttle block.

Such pins can be made of very hard steel, porcelain or other wear resistant material and can be replaced if they break or wear down without affecting the rest of the shuttle block.

The important feature is that the bottom of this eye projection preferably is in a plane with the bottom of the rest of the shuttle block and there are at the bottom two downwardly extending legs one behind and one in front of the eye hole. One leg I will call for convenience the back leg while the other in front of this I will call the front leg which is shorter than the back leg whereby there is an entering passage forming part of the threading slot down under the front leg and then up between the two legs into the eye hole proper.

This eye hole extends crossways through the eye projection and the threading block into the threading chamber in front of a center or angle pin so that when threaded the thread passes part way through the threading chamber and thence around this center pin and out through the shuttle eye hole.

I utilize the fact that along the eye side of almost every shuttle there is a thread groove of

2

segmental contour by providing an eye outlet in the wood, forming part of the block recess, which extends down and out at the side and at the bottom is so arranged that its top edge will be part of the thread groove and will project slightly above or overlap the bottom of the front leg, there being also a space laterally between the front leg and the inside of the wood below the eye outlet in the wood to permit the thread to go down through the threading slot and up into the eye but to prevent its coming out.

I prefer to have a strip or layer of fibre or other tough, wear resistant, hard material along the eye side of the shuttle in which the thread groove is formed and in which is formed the bottom of the eye outlet.

I prefer to use a threading block with an extra long bearing surface where it rests on the wood in the block recess to prevent rocking or loosening as either might cause some part of the threading slot to be too narrow and tend to break the thread while it was threading.

In the drawings,

Fig. 1 is a plan view of the front or eye end 25 of a shuttle with a shuttle block of my construction in place and with the thread from a bobbin passing out of the eye.

Fig. 2 is a perspective view looking down from the front and side of the shuttle block shown in 30 Fig. 1 when removed from the shuttle.

Fig. 3 is a sectional view on line 3—3 of Fig. 1 through the wood, the shuttle block being shown in elevation.

Fig. 4 is an enlarged side elevational view from 35 the eye side of the shuttle shown in Fig. 1 with parts broken away.

Fig. 5 is a plan view similar to Fig. 1, showing a somewhat modified type of shuttle and block and Fig. 6 is a side elevation of a shuttle block 40 of the type shown in Fig. 5 removed from the shuttle.

Fig. 7 is a sectional view through the wood on line 7—7 of Fig. 1, but with the shuttle block in elevation, the cut away part of the eye outlet in the wood being shown with a somewhat wider thread groove than that shown in Fig. 3.

Fig. 8 is a view of part of the bottom of a shuttle block with bearing pins in place and Fig. 9 is a detail of a preferred construction of my 50 thread trap.

In the drawings Figs. 1 to 4 show a shuttle with the preferred embodiment of my invention. A represents a shuttle with the usual tip 10 and a bobbin chamber 1 in which the bobbin B is positioned so that the thread T can unwind

through a threading chamber 6 in the metal block G in front of which is a thread recess 17 which extends along and forward near tip 10. There is also in the side of the shuttle body a thread groove 20 of segmental contour with a bottom edge 24 and the top edge 25.

There is also a block recess indicated altogether by C in which the threading block G fits. Recess C has a bottom 21, a front part 18 with a downwardly and backwardly sloping back edge 11 and an eye outlet 26 in the wood body. The bottom of eye outlet 26 at 28, as shown, coincides with the bottom edge 24 of the thread groove 20 and inside this the wood is cut away at 27 to form part 51 of the threading slot F which extends from under guide 1 and nose 9 into the eye hole 36.

The threading block G has sides 3 and 4 which, as shown, are of V-shape and the whole block is much longer than those commonly used so that it will counteract the tendency of some blocks to gradually wear loose on the attaching screw S which passes through the side of the shuttle at 40 and the shuttle block at 41 to hold the block in place.

This block G has a bottom 5 which, as shown, coincides with the bottom 21 of recess C and 43 of the back leg 31 and has a threading chamber 6 which extends from the front of the bobbin chamber 1 towards the nose 9 which is under and a little to the side of the overhanging guide 7, both of well known form. It also has a front leg 32 which is shorter than leg 31 and there is therefore a passage 52 under its bottom 33 forming part of threading slot F.

At 2 there is an eye projection extending out towards what I will call the eye side of the shuttle and through this extends an eye hole 36 at the bottom of which is an inlet 37 with an outside 38, there being also at its inside or inner end a center or angle pin 65 around which the thread bends when it runs from the threading chamber 6 through the eye hole 36 and thence to the outside 38.

The front edge 30 of this eye projection 2 extends a little forward of the back edge 11 near the front of the block recess C, leaving a space 50 which forms part of the threading slot F which connects with the space 52 at the bottom 33 of the front leg 32 passing around the curved part 34 of the front edge, thence up between the front and back legs 32 and 31 as part 37 of slot F into the eye hole 36.

Preferably I form holes 14 and 16 in the back leg and the front leg and up through these I drive the bearing pins 13 and 15 so that when the thread T is actually threaded and is passing out the eye hole 36 and is moving back and forth in the thread groove 20, they will take up the wear. One or both friction pins 13 and 15 can be cemented into place in its pin hole preferably with an adhesive which can be softened by heat if it becomes necessary or desirable to remove a pin so as to replace it with a new one.

43 is the bottom of the back leg 31 and as shown, is level with the bottom 21 of the block recess, of the bottom 5, of block G and of the cut away part 21. 33 is the bottom of the front leg 32, which, as shown, is curved at 34 and is spaced at 52 from the bottom 21 of the block recess to allow the thread to pass.

As shown in Figs. 5 and 6, there may be modifications of my trap as follows:

The shuttle body, except for the V-shaped cut away part to fit the V-shaped sides 3 and 4 is the same as in the first construction.

A represents a shuttle body of a well known

type with a bobbin chamber 61, the end of which at 62 is rounded, and H represents a shuttle block which does not have the V-shaped legs shown and described but ends at the point 60. It has the usual fastening hole 41 and downward projection 42 as well as the guide 7 and eye projection 64 similar to 2, these parts being the same as in the other views but instead of using pins driven into holes extending upwards in the long and short legs, I show the short leg 45 and the long leg 46 with no pin holes but there is the passage 47 between them into an eye hole 48.

This shuttle block H may be of chromium plated metal or may be made of some other hard metal, but in any event, the bottom of short leg 45 should extend a trifle below the bottom edge 28 of the eye outlet, such as 26, in the wood, but not down to the bottom of part 52 of the threading slot F and of the cut away part 27.

The front edge of eye projection 64, is preferably positioned in front of the back edge 11 of the shuttle block recess in the wood but while such a projection or overlapping is desirable, it is not absolutely necessary.

The threading slot F which is made up of the parts 50, 52, and 51, connecting with the parts such as 37 or 47, of the bottom entrance into the eye passage in the eye block must be free and clear to permit of easy threading.

As shown in Fig. 4, the bottom 29 of the eye outlet in the wood coincides with the bottom edge 24 of the thread groove 20 but as shown in Fig. 7, there may be a wider thread groove 29, the bottom 24 of which is below and parallel with the bottom edge 28 of the eye outlet in the wood.

As shown in Fig. 7, there may be a strip of fibre O along the eye side in which thread groove 29 is formed and in which is formed the bottom edge 28 of the eye outlet, the wood being cut away at 27, leaving the fibre on the outside.

I prefer to have friction plates E of the spring pressed type and extending down and forward, similar to those shown in patent to Park, No. 2,087,607 of July 20, 1937, and in addition to this, I prefer to have the back friction pin 78, as shown in Fig. 9, sloping down and forward while the front pin 71 can be vertical and I also prefer to show a relatively narrow thread groove 72 along the side of the shuttle so that its bottom edge 74 will be above the bottom edge 73 of the eye outlet in the wood.

The friction plates take out the kinks, help to keep the thread from running wild and tend to keep the thread down while the pin 78 tends to keep it up and the narrow groove 72 helps them both to keep it in the right position to engage pin 70 in one direction and pin 71 in the other direction and away from the metal parts of the shuttle block.

These parts therefore all help the overlapping of the bottom edge of the eye outlet in the wood and the bottom of the front leg and the overlapping of the front edge, such as 30, of the block and the back edge 11 of the front of the shuttle block recess in the wood to prevent unthreading. The overlapping of the bottom of the eye outlet and the bottom of the front leg and of the back edge of the front of the block recess and the front of the block are the most necessary features of my shuttle eye thread trap.

I claim:

1. The combination with a shuttle of the automatic type having a body with a thread eye in its side near its front end, a thread groove along the eye side, a bobbin chamber, and a shuttle block

recess extending from a point in front of the thread eye back to the bobbin chamber, said shuttle block recess including a diagonal front wall and an eye outlet in the side which extends down into and along the thread groove in the side, the stock on the inside from the bottom of the eye outlet being cut away down to the bottom of the shuttle block recess; of a shuttle block positioned in the shuttle block recess, including a longitudinal threading chamber and a nose on one side of the threading chamber near the front of the shuttle block recess and an eye projection which extends into the eye outlet in the wood, said shuttle block including a guiding front edge extending diagonally down and back from said nose, spaced from and extending forward of the back edge of the front wall of the shuttle block recess, to a front leg extending down below the bottom of the eye outlet to near the bottom of the shuttle block recess, and a back leg extending down to the bottom of said recess, there being a passage under the front leg and an inlet passage between the two legs up into an eye hole in the shuttle block, there being upwardly extending holes from the bottom of the front leg and from the bottom of the back leg, together with friction pins of hard material positioned one in the hole in the front leg and the other in the hole in the back leg, the hole and the pin in the back leg sloping down and forward; and friction plates extending down and forward into the threading chamber.

2. The combination with a shuttle of the automatic type having a body with a thread eye in its side near its front end, a thread groove along the eye side, a bobbin chamber, and a shuttle block recess extending from a point in front of the thread eye back to the bobbin chamber, said shuttle block recess including a diagonal front wall and an eye outlet in the side which extends down into and along the thread groove in the side, the stock on the inside from the bottom of the eye outlet being cut away down to the bottom of the shuttle block recess; of a shuttle block positioned in the shuttle block recess, including a longitudinal threading chamber and a nose on one side of the threading chamber near the front of the shuttle block recess and an eye projection which extends into the eye outlet in the wood, said shuttle block including a guiding front edge extending diagonally down and back from said nose, spaced from and extending forward of the back edge of the front wall of the shuttle block recess, to a front leg extending down below the bottom of the eye outlet to near the bottom of the shuttle block recess, and a back leg extending down to the bottom of said recess, there being a passage under the front leg and an inlet passage between the two legs up into an eye hole in the shuttle block, there being upwardly extending holes from the bottom of the front leg and from the bottom of the back leg, together with friction pins of hard material positioned one in the hole in the front leg and the other in the hole in the back leg, the hole and the pin in the back leg sloping down and forward.

3. The combination with a shuttle of the automatic type having a body with a thread eye in its side near its front end, a thread groove along the eye side, a bobbin chamber, and a shuttle block recess extending from a point in front of the thread eye back to the bobbin chamber, said shuttle block recess including a diagonal front wall and an eye outlet in the side which extends down into and along the thread groove in the side, the stock on the inside from the bottom

of the eye outlet being cut away down to the bottom of the shuttle block recess; of a shuttle block positioned in the shuttle block recess, including a longitudinal threading chamber and a nose on one side of the threading chamber near the front of the shuttle block recess and an eye projection which extends into the eye outlet in the wood, said shuttle block including a guiding front edge extending diagonally down and back from said nose, spaced from and extending forward of the back edge of the front wall of the shuttle block recess, to a front leg extending down below the bottom of the eye outlet to near the bottom of the shuttle block recess, and a back leg extending down to the bottom of said recess, there being a passage under the front leg and an inlet passage between the two legs up into an eye hole in the shuttle block, there being upwardly extending holes from the bottom of the front leg and from the bottom of the back leg, together with friction pins of hard material positioned one in the hole in the front leg and the other in the hole in the back leg.

4. The combination with a shuttle of the automatic type having a body with a thread eye in its side near its front end, a thread groove along the eye side, a bobbin chamber, and a shuttle block recess extending from a point in front of the thread eye back to the bobbin chamber, said shuttle block recess including a diagonal front wall and an eye outlet in the side which extends down into and along the thread groove in the side, the stock on the inside from the bottom of the eye outlet being cut away down to the bottom of the shuttle block recess; of a shuttle block positioned in the shuttle block recess, including a longitudinal threading chamber and a nose on one side of the threading chamber near the front of the shuttle block recess and an eye projection which extends into the eye outlet in the wood, said shuttle block including a guiding front edge extending diagonally down and back from said nose, spaced from and extending forward of the back edge of the front wall of the shuttle block recess, to a front leg extending down below the bottom of the eye outlet to near the bottom of the shuttle block recess, and a back leg extending down to the bottom of said recess, there being a passage under the front leg and an inlet passage between the two legs up into an eye hole in the shuttle block.

5. The combination with a shuttle of the automatic type having a body with a thread eye in its side near its front end, a thread groove along the eye side, a bobbin chamber, and a shuttle block recess extending from a point in front of the thread eye back to the bobbin chamber, said shuttle block recess including a diagonal front wall and an eye outlet in the side, the stock on the inside from the bottom of the eye outlet being cut away; of a shuttle block positioned in the shuttle block recess, including a longitudinal threading chamber, a nose on one side of the 60 threading chamber near the front of the shuttle block recess and an eye projection which extends into the eye outlet in the wood, said shuttle block including a guiding front edge extending diagonally down and back from said nose, spaced 65 from the front wall of the shuttle block recess, to a front leg extending down below the bottom of the eye outlet to near the bottom of the shuttle block recess, and a back leg extending down to the bottom of said recess, there being a passage 70 under the front leg and an inlet passage be- 75

tween the two legs up into an eye hole in the shuttle block.

6. The combination with a shuttle of the automatic type having a body with a thread eye in its side near its front end, a thread groove along the eye side, a bobbin chamber, and a shuttle block recess extending from a point in front of the thread eye back to the bobbin chamber, said shuttle block recess including a diagonal front wall and an eye outlet in the side, the stock on the inside from the bottom of the eye outlet being cut away; of a shuttle block positioned in the shuttle block recess, including a longitudinal

threading chamber, a nose and an eye projection which extends into the eye outlet in the wood, said shuttle block including a guiding front edge extending diagonally down and back from said nose, spaced from the front wall of the shuttle block recess, to a front leg extending down below the bottom of the eye outlet, and a back leg extending down to the bottom of said recess, there being a passage under the front leg and an inlet passage between the two legs up into an eye hole in the shuttle block.

WILFRID JOSEPH GOSELIN.
